UNITED STATES PATENT OFFICE.

CHARLES HERRMAN, OF NEW YORK, N. Y.

NUT AND BOLT-HEAD WRENCH.

1,297,846.

Specification of Letters Patent. Patented Mar. 18, 1919.

Application filed December 28, 1917. Serial No. 209,352.

To all whom it may concern:

Be it known that I, CHARLES HERRMAN, a citizen of the United States, residing at New York, in the county of New York and State of New York, have invented certain new and useful Improvements in Nut and Bolt-Head Wrenches; and I do hereby declare the following to be a full, clear, and exact description of the invention, such as will enable others skilled in the art to which it appertains to make and use the same.

This invention relates to nut and bolt-head wrenches and it has for an object to provide a jaw formation by which each end of a double ended wrench may have a capacity for a plurality of sizes of nuts or bolt-heads.

A further object of this invention is the provision of a wrench head having jaws formed to accommodate several sizes of nuts or bolt-heads, and having said jaws so formed as to have certain parts thereof reinforce those parts upon which strain is exerted when in use.

A further object is the provision of a wrench head having jaws formed therein and having the adjacent faces of said jaws in stepped formation having corresponding steps on each of the jaws to present sockets but having the steps of each of the jaws offset varyingly, in varyingly substantial parallelism so that by two or three sets of step faces, three or four sizes of nuts or bolt-heads may be accommodated.

Further objects will be apparent from the following specification, appended claims and drawings thereof, in which,

Figure 1 is a perspective view of the wrench showing the features of this invention incorporated therein,

Fig. 2 is an end elevation thereof,

Fig. 3 shows a slightly modified form, and

Fig. 4 is a perspective view of a mode of using the wrench.

Referring to the drawings in which the several features of this invention are clearly shown, 10 indicates a handle portion of a double-ended wrench having the wrench heads 11 and 12 formed at the opposite ends of the handle member. Each of these heads is formed into the jaws 13 and 14 which have their adjacent faces stepped as at 15. These jaws have corresponding portions and have the steps offset to a greater extent at one side than at the other, as shown clearly in Fig. 2, so as to allow the faces 16, 17, 18

and 19 respectively to be used in gripping nuts or bolt-heads in various combinations. That is, for one size of bolt-head having a transverse dimension indicated at "C," the faces 16 and 17 are used, for an intermediate size indicated by "B," the faces 18 and 19 are used, but for the smallest size indicated at "A," the faces 17 and 18 are used, so it is thereby seen that three different sizes of nuts may be gripped by the wrench by portions of the jaws. As shown in Figs. 1 and 2, it is possible for a single wrench with two sets of jaws in staggered relation to accommodate six sizes of nuts. As to Figs. 1 and 2 it may also be noted, the weakest portion of a wrench jaw is on lines $x-x-x$ at the junction of the jaw faces and crotch and the weakness of this line on jaw 13 when either of the faces 16 or 18 is used is compensated for by the material forming the other face, as the case may be, and similarly, the weakness of the jaw 14 is compensated for by the metal forming either of the faces 17 or 19, which is not being used. This enables a maximum strength jaw with a minimum of bulk and metal, a saving in quantity production, and a greater manipulative ease in restricted spaces and corners.

The offsets which produce the stepped formation of the faces 16, 17, 18 and 19 are indicated at 15^a and 15^b, and the curved, or otherwise formed faces, which connect the ends of the faces 16, 17, 18 and 19 across the crotch may be identified by the characters 16^a and 18^a, respectively. The offsets 15^a and 15^b continue between the curved faces 16^a and 18^a, to a common meeting point which occurs at the intersection of the curved planes of the faces 16^a and 18^a. These offsets are inverted relatively on the opposite sides of the meeting point. It may further be noted that the crotch, curved faces 16^a and 18^a are eccentric with respect to each other in the separate companion sets of faces.

When the faces 17 and 18 are being used, the tendency of the strain exerted upon the wrench to twist the jaws 13 and 14 occurring in the contact of one of the faces 17 or 18 is counteracted by the other of the faces so it is seen that the wrench may be equally as convenient in use for any of the several sizes.

In Fig. 3, the jaws 20 and 21 are stepped to form the faces 22, 23, 24, 25 and 26. In this type, the faces 22 and 23 receive the

largest size nut, the faces 22 and 24 the next size nut, the faces 25 and 26 the next succeeding standard size of nut, while the faces 24 and 25 will accommodate the smallest size 5 of nut. In this type of wrench-head, four sizes of nut-gripping jaws may be formed in a single wrench-head having median lines of each of the pairs of gripping surfaces parallel and set to the desired angle with 10 respect to the median line of the handle.

It is evident in view of the foregoing, that numerous modifications may be made in view of the appended claims without departing from the spirit of this invention, and no 15 limitation is implied by the drawings which are submitted for illustrative purposes only.

Having thus described this invention, I claim:

1. In a nut and bolt-head wrench, spaced 20 jaws having parallel stepped faces and having the corresponding steps of the opposite jaws offset to different extents to accommodate as many different sizes of nuts and bolt-heads as the number of sets of corresponding 25 steps plus one.

2. In a nut and bolt-head wrench, spaced jaws having parallel-faced steps, said steps differing as to width of offset, said offsets being inverted in the opposite faces of the 30 jaw and being right-angular thereto, and said offsets facing obversely and reversely respectively from the same horizontal plane.

3. In a nut and bolt-head wrench, spaced jaws having parallel-faced steps, said steps differing as to width of offset, said offsets being of a uniform width along each jaw, and said offsets being of a broken and inverted continuity through the crotch and 35 junctional section of the wrench jaws.

4. In a nut and bolt-head wrench, spaced jaws having parallel-stepped faces, said steps being disposed in horizontal plane companionships, the vertical planes of the innermost step faces of each set being un- 40 obstructed, and the vertical planes of the outermost step faces of each horizontal companion set being one-way obstructed by the inward stepping of the respective innermost stepped jaws.

5. In a nut and bolt-head wrench, spaced jaws having parallel-stepped faces, said steps being disposed in horizontal plane companionships, the vertical plane of the innermost gripping face of one step and the 55 vertical plane of the innermost face of the other step being unobstructed and forming thereby an additional nut and bolt-head engaging means.

6. In a nut and bolt-head wrench, spaced 60 jaws having parallel-stepped faces, said steps differing in the respective jaws in the width of offset, said steps being in paired 65 companionship in differing horizontal plane levels, the gripping faces of one companion set respectively overlapping and exposing the

contiguous vertically associated gripping faces of another companion set in another horizontal plane.

7. In a nut and bolt-head wrench, spaced 70 jaws having parallel-stepped faces, the overlapping advanced step face of one jaw being companion to the retracted step face of the opposing jaw, and the retracted step face of the first mentioned jaw being companion to the projecting advanced step face of the 75 afore-mentioned opposing jaw, and the so constituted companion sets forming a range of differing sizes of opening, and the overlappingly advanced step face of one jaw companioned by the projectingly advanced step 80 of the other, opposing, jaw forming between their parallel vertical planes the third differing sized opening and thereby making possible the formation of a double open ended nut and bolt-head wrench having a plurality 85 of up to six differing sized openings.

8. In a nut and bolt-head wrench, spaced jaws having parallel-stepped faces, having the distances between each pair to accommodate nut or bolt heads of different dimensions, and having the stepped faces offset 90 so that the projecting step of one pair of steps presents a reduced opening with the projecting step of the other pair of steps.

9. In a one-piece, one-way opening nut 95 and bolt-head wrench, jaws in parallel step formation, said steps differing as to width of offset, the step formation in one jaw being in inverted order with respect to that of the opposite jaw so that an additional nut 100 and bolt-head opening is formed for the number of sets of faces.

10. In a one-piece, one-way opening nut and bolt-head wrench, spaced jaws having 105 parallel stepped faces, said steps being disposed in horizontal plane companionship, the included space of each plane being suitable for a different size of nut or bolt-head, there being a plurality of such planes, said stepped faces in each companion set forming 110 an individual socket, and the innermost face of one jaw coacting with the innermost face of the other jaw in another set of companion faces forming a socket for a smallest size nut and bolt-head. 115

11. In a nut and bolt-head wrench, a plurality of faces comprising a pair of co-ordinate faces for each adopted size of nut or bolt-head having the separate pairs offset and staggered to utilize one face of each 120 pair to form an additional and smallest nut and bolt-head engaging socket.

12. In a one-piece, nut and bolt-head wrench, comprising a longitudinal central holding and handle member, of any suitable 125 configuration, each end of said handle having an enlarged head formed thereon, said heads having nut and bolt head engaging jaws formed therein, said jaws being of stepped formation with offsets of said steps 130

differing in the respective stepped faces, and said offsets facing obversely and reversely relative to a horizontal plane including them.

5 13. In a one-piece, one-way opening nut and bolt-head wrench, spaced jaws in parallel stepped formation, said steps being disposed in horizontal planes, the step formation in one jaw being in inverted relation to that in the other jaw, the offsets of said steps differing as to width, and the horizontal plane passing through the said offsets having an opening, as between the said offsets, accommodating an additional and

15 smallest size nut and bolt-head.

14. In a nut and bolt-head wrench, spaced jaw members having stepped contact faces, with companion step portions in the separate jaws, the companion step portions in 20 the jaws being joined by curved faces at the base of said jaw members, the offset portions formed in the stepped faces being of different widths in the opposite jaws, said off-

sets being oppositely formed in said stepped faces, and continuing between the curved 25 faces at the base of said companion step faces to a common point, and said curved faces being eccentric with respect to each other in the separate companion sets of faces.

30 15. In a one-piece, one-way opening nut and bolt-head wrench, spaced jaws having parallel stepped faces, said steps disposed in a plurality of horizontal planes, the faces of said steps being disposed in a suitable 35 plurality of vertical planes, the vertical planes of the innermost steps of each side being unobstructed and the other remaining, vertical planes of the retracted faces being one way obstructed, and the unobstructed 40 vertical planes of the innermost steps forming therebetween an additional, differing and smallest size nut and bolt-head engaging opening.

45 In testimony whereof I affix my signature. CHARLES HERRMAN.
